WILLIAM TAYLOR, OF LEICESTER, ENGLAND.

METHOD OF AND APPLIANCE FOR POLISHING GLASS AND THE LIKE SUBSTANCES.

1,409,888.

Specification of Letters Patent. Patented Mar. 14, 1922.

Application filed May 17, 1919. Serial No. 297,777.

To all whom it may concern:

Be it known that I, WILLIAM TAYLOR, a subject of the King of Great Britain, and resident of Stoughton Street Works, Leicestershire, in the county of Leicester, England, have invented a certain new and useful Improvement in Methods of and Appliances for Polishing Glass and the like Substances, of which the following is a specification.

10 This invention relates to methods of, and means for, polishing glass and the like substances by means of powdered abrasive such as rouge in a liquid vehicle or lubricant, and its object is to provide a method and means 15 whereby, during the process of polishing, the supply of lubricant, or lubricant and abrasive, is effected automatically as required.

This may be done, according to my invention, by taking advantage of the varying adhesion, that is, the frictional resistance to relative movement, which takes place between the polishing tool and the work as the polisher becomes dry.

25 In polishing machines means are provided for effecting a relative motion of the tool and work to cause the polishing. Such means may comprise means for moving one of these members while retaining the other 30 stationary, or means for moving each of the members. It should be understood that the expression "means for causing a relative motion" of the polishing members is intended to cover any means for controlling the 35 movement or position of each member in such a way that the contacting surfaces of the members move with respect to one another.

The manner in which the frictional resistance between the polishing tool and the work varies depends to some extent upon the material of which the polishing tool is made. For the sake of illustration, I shall describe the use of the invention in connection

45 with polishing machines in which the face of the polishing tool is formed of wax or any similar substance which is comparatively impervious to the lubricant, although the invention is by no means limited to use 50 in connection with such polishers. When tools of such materials are used, the frictional resistance between the tool and the work generally increases as the polisher becomes dry.

55 In machinery for polishing glass it is usual to employ a rubber or polisher having

a face whose form is a counterpart of that required on the work, the polisher being moved about the work by means of a crank. One method, therefore, according to which 60 my invention may be carried out is to connect the crank to the crank-shaft which operates it, by means of a dynamometer which may be adjustable so that it shall yield when, as the polisher becomes dry, the 65 adhesion between the polisher and the work rises to a predetermined amount, and the yielding of the dynamometer may be made to actuate, for example, a pneumatically-controlled valve which may supply liquid on 70 to the surface of the work or polisher. Such liquid may contain abrasive in suspension in known manner.

Another method which may be used to control the supply of liquid is to provide, 75 for moving the polishing tool, a non-rotary finger adapted to yield laterally in one direction against the action of a spring, which may be adjustable. Normally the finger is held by the spring in its seating in an actuating member, but as the adhesion between the polisher and the work rises to the predetermined amount, the finger is displaced thereby from its seating and may be adapted to actuate at such time the liquid supply 80 valve or equivalent device.

In some polishing machines the work is held on a suitable holder on a slowly-rotating spindle, and the polisher is moved in a circular path upon the moving work, so 90 that relatively they describe a cylindrical path. At one part of such circular path the velocity of rubbing is the sum of the velocities of the two motions, and at other parts it is less than the sum and thus the resistance to motion which increases as a whole as the polisher becomes dry varies continuously from a maximum to a minimum during each complete movement of the 95 polisher.

100 This fact I may utilize, according to the present invention, in order to supply the liquid intermittently and as required at one part only of the motion of the polisher, for example, at the point in such motion at 105 which, momentarily, the surface of the work is most exposed by the movement of the polisher. In this way I economize lubricant and abrasive.

Other devices may, of course, be used to 110 control the supply of liquid at the critical time, and means other than a pneumatically

controlled valve may be used for supplying the liquid or abrasive.

In the accompanying drawings, which illustrate by way of example one means of carrying out the invention, Figure 1 is a diagrammatic and partial view showing in plan three lens-polishing units of a range comprised in a single polishing machine. Figure 2 is a diagrammatic front elevation 10 of the same, showing also means for maintaining circulation in the lubricant feed-pipe. Figures 3 and 4 are respectively a detailed plan view and side elevation of part of the apparatus appearing in Figure 1; Figure 5 is a detailed plan view of one of the nozzles appearing in Figure 1; Figure 6 is a horizontal longitudinal section of the part of the apparatus shown in Figure 3; Figure 7 is a view similar to Figure 5 showing a modified form of nozzle. Figures 3, 4, 5, 6 and 7 being drawn to a larger scale than Figures 1 and 2.

In Figures 1 and 2 *a* and *b* represent, in the case of each lens-polishing unit, two tool-members to either of which the work may be attached whilst the other member is the polisher; it being understood that there is caused by known means a relative movement of these members whereby the coacting surfaces of the work and polishing member are rubbed together mechanically. *c* are nozzles supplied from a pipe *c*¹ with lubricant (for lubricant and abrasive) and adapted to project the same onto the exposed portion 30 of the member *a*; whilst Figure 1 also shows at *e*, in the case of each lens-polishing unit, that part of the operating machine which serves to carry a finger (usually ball-pointed) whereby the member *b* is engaged and 35 moved, and whereby in accordance with the present invention a spray of lubricant (and rouge or other abrasive) is pneumatically controlled as hereinafter explained.

The portion *e* of the mechanism (Figure 45 1) is illustrated in detail in Figures 3 and 4, wherein *d* is a bar adjustably clamped, by means of a screw *g*, in an arm *f* whereby the upper tool-member *b* is moved over the surface of the lower tool-member *a* in a substantially circular path by usual mechanically-actuated means (not shown); the bar *d*, which is tubular, being connected by a flexible tube *h* to an air-pipe (plenum or vacuum) hereinafter mentioned. The bar *d* 50 has an arm *d*¹ which carries a pivot pin *i* whereon a link *j* is pivoted, the link *j* having a hole *j*¹ in which a ball-pointed finger *j*² for engaging and moving the member *b* is adjustably clamped by means of a screw *j*³. 55 The link *j* also carries a valve *j*⁴ adapted to control an opening at the outer end of the tubular bar *d*; this opening being surrounded by a bush *d*² (preferably of fibre or the like) adapted to afford an elastic seating for 60 the valve *j*⁴. The link *j* is moved in the di-

rection to cause the valve *j*⁴ to close against its seating *d*² by the action of a helical spring *k* which is contained in a tubular holder *k*¹ pivoted at *k*² to the bar *d*, the spring *k* being held under compression between a ball *k*⁴ 70 which rests in a peripheral groove on the pivot-pin *k*² and a plunger *k*⁵ which fits slidably in the holder *k*¹ and is forced by the spring outwards against the arcuate edge of an arm *j*⁵ on the link *j*. The ball *k*⁴ serves 75 to retain the holder *k*¹ upon the pivot-pin *k*² whilst permitting angular adjustment of the holder about the pivot; such adjustment which may be determined with the aid of 80 graduations marked upon the arm *j*⁵ as indicated, serving to vary as desired the turning-moment exerted, about the axis *i*, by the spring *k* against the arm *j*⁵ and link *j*, and consequently to vary the effective pressure 85 with which not only is the ball-pointed finger *j*² retained in normal position but also the valve *j*⁴ is held closed against its seating *d*², yet without altering the stress of the spring *k* itself. For the purpose of limiting the movement of the link *j* about the 90 pivot *i* an adjustable stop *d*³ may be provided on an arm *d*⁴ of the bar *d*.

One of the spraying-nozzles *c* on the pipe *c*¹ (Figures 1 and 2), is shown in greater detail in Figure 5, which shows the nozzle-outlet as controlled by a needle-valve *c*³ the stem *c*² of which, extending across the pipe *c*¹ is attached to a piston *c*⁴ fitted to slide in a cylinder *c*⁵. The piston *c*⁴ is urged by a spring *c*⁶ in the direction to open the valve 95 *c*³, the opening movement being adjustably limited by a screw *c*⁹ which passes through the rear closure *c*⁷ of the cylinder *c*⁵; whilst by way of a flexible tube *c*⁸ the cylinder communicates at its rear end (i. e. at the 100 side of the piston *c*⁴ opposite to the spring *c*⁶) with a branch *p*¹ on a pipe *p* which is supplied with air under pressure from any convenient source. The branch *p*¹ is adjustably controlled by a throttle-valve *p*², between which and the junction of the flexible tube *c*⁸ the flexible tube *h* (already mentioned) is connected to the branch *p*¹; the 105 adjustment of the valve *p*² serving to determine the volume and duration of the emission from the nozzle *c*. A constant circulation of lubricant (or lubricant and abrasive) is maintained in the pipe *c*¹, but so long as the air in the branch *p*¹ remains at a pre-determined pressure, the air-pressure within 110 the cylinder *c*⁵ is sufficient to overcome the force of the spring *c*⁶ and the needle-valve *c*³ remains closed. When, however, the adhesion between the work and the polishing-tool (i. e. between the members *a* and *b*) 115 rises so far as to cause the link *j* to move so as to open the valve *j*⁴, air escapes through this valve from the branch *h*, thus reducing the air-pressure within the tube *c*⁸ and cylinder *c*⁵, with the result that the needle-valve 120

c^3 is opened by the spring c^6 so as to permit a jet of lubricant (or lubricant and abrasive) to be projected onto the tool-member a from the nozzle c .

- 5 If, instead of a plenum, or positive pressure, a vacuum, or negative pressure is maintained in the air-pipe p , the tube c^8 would be connected to the cylinder c^5 at the same side of the piston c^4 as the spring c^6 as shown in 10 figure 7; the action of the spring c^6 being in such case normally opposed by the vacuum in the cylinder c^5 , but permitted to become effective when, owing to the opening of the valve j^4 , air is admitted through the tube h 15 to the branch c^8 . The term "pressure" as used in the claims is to be understood as including negative as well as positive pressure.

Figure 2 illustrates one arrangement for maintaining a constant circulation of rouge 20 and water (or equivalent abrasive and lubricant) through the pipe c^1 . The mixture of rouge and water is contained in a tank l wherein is mounted a centrifugal pump l^1 driven by power from any convenient source, 25 as for example by a belt l^2 passing over a guide-pulley l^3 and around a pulley l^4 on the pump-spindle as indicated. The outlet m of the pump is connected to the circulation-pipe c^1 , which may be of rubber so as to 30 facilitate the independent adjustment of the positions of the nozzles c , and this pipe c^1 terminates in an upright stand-pipe n affording a constant head of liquid; the pipe n delivering into the mouth o of a return-pipe o^1 35 through which the surplus liquid is led back to the tank l . Constant and fairly rapid circulation is necessary in order to prevent deposition of the abrasive in the pipe c^1 .

When the apparatus is in use and the surfaces of a pair of tool-members a and b have 40 been moistened (either by the jet from the nozzle c , or otherwise) polishing proceeds until the polishing-tool becomes sufficiently dry to render the polishing action most 45 efficient; a stage which is easily recognized by an experienced attendant. At this moment the point whereat the spring k exerts its thrust against the arm j^5 of the link j may be so set that, at each to-and-fro movement 50 of the finger j^2 , the valve j^4 is caused to open so as to release air from the tubes h and c^8 and thus bring about the opening of the needle-valve c^3 and the consequent discharge of lubricant and abrasive from the 55 nozzle c . When sufficient lubricant has been deposited upon the surface of the tool-member, the adhesion and resulting traction between them is so diminished that the valve j^4 is permitted to close under the action of the 60 spring k with the result that the air-pressure within the tubes h and c^8 again rises (at a rate dependent upon the adjustment of the throttle-valve p^2) until, the force of the spring c^6 being eventually overcome, the

needle-valve c^2 closes and stops the discharge 65 from the nozzle c . Preferably, the direction in which the finger j^2 is movable to open the valve j^4 is such that the valve is opened and the jet issues from the nozzle c at the moment when the adjacent portion 70 of the surface of the tool-member a is most exposed by the withdrawal therefrom of the tool-member b .

I claim:—

1. The method of controlling the supply 75 of liquid lubricant in the polishing of a surface by means of a polishing member, said polishing member and the work being moved relatively to one another to effect the polishing, which method comprises increasing the 80 supply of the liquid to said surface when the frictional resistance between the surfaces of the polishing member and the work exceeds a predetermined amount, and decreasing the supply when said frictional re- 85 sistance falls below a predetermined amount.

2. The method of controlling the supply of liquid lubricant and abrasive in the polishing of a surface by means of a polishing member, said polishing member and the work 90 being moved relatively to one another to effect the polishing, which method comprises circulating the liquid in a container to keep the abrasive in suspension in the liquid, increasing the supply of the liquid and abrasive to one of said surfaces when the frictional resistance between the surfaces of the 95 polishing member and the work exceeds a pre-determined amount, and decreasing the supply when said frictional resistance falls 100 below a predetermined amount.

3. The method of controlling the supply of liquid lubricant in the polishing of a surface by means of a polishing member, said polishing member and the work being moved 105 relatively to one another to effect the polishing, which method comprises utilizing the variation of frictional resistance between the surfaces of the work and polishing member to effect variation of the supply of lubricant. 110

4. The method of supplying liquid lubricant in the polishing of surfaces by means of a polishing member, said polishing member and the work being moved relatively to one another to effect the polishing, which method 115 comprises supplying the liquid automatically in predetermined amount and intermittently whenever the frictional resistance between the surfaces of the work and polishing member reaches a predetermined limit. 120

5. The method of supplying liquid lubricant in the polishing of surfaces by means of a polishing member, said polishing member and the work being moved relatively to one another to effect the polishing, which 125 method comprises supplying the liquid automatically, intermittently, and at a predetermined rate for a predetermined interval of

time, whenever the frictional resistance between the surfaces of the work and polishing member reaches a predetermined limit.

6. In apparatus for supplying lubricant to a polishing machine having cooperating work holding and polishing members and means for causing relative motion between said members for producing relative movement between the coating surfaces of the 10 polishing member and the work, the combination of means for supplying lubricant to one of said surfaces, and means operated by variation of the friction between said surfaces for controlling the supply of lubricant.

7. In apparatus for supplying lubricant to a polishing machine having cooperating work holding and polishing members and means for causing relative motion between 20 said members for producing relative movement between the coating surfaces of the polishing member and the work, the combination of lubricant supply means having an outlet for discharging lubricant onto one of 25 said surfaces, a controlling valve for said outlet, means for exerting constant yielding pressure on said valve in the direction to cause it to open, holding means for keeping said valve normally closed, and controlling 30 means operated by variation of the friction between said surfaces to render said holding means inoperative and permit said valve to open when the friction between said surfaces reaches a predetermined value.

8. In apparatus for supplying lubricant to a polishing machine having cooperative work holding and polishing members and means for causing relative motion between 40 said members for producing relative movement between the coating surfaces of the polishing member and the work, the combination of means for supplying lubricant to one of said surfaces, and means for controlling the supply of lubricant, connected 45 to said moving means and operated by variation in the load on said moving means resulting from variation in friction between the work and the polishing member.

9. In apparatus for supplying lubricant to a polishing machine having cooperating work holding and polishing members and means for causing relative motion between 50 said cooperating members for producing relative movement between the coating surfaces 55 of the polishing member and the work, said means including a moving member, the combination of an engaging member adapted to engage one of the aforesaid cooperating members and transmit motion of the 60 moving member thereto, means adapted to connect said engaging member to said moving member and permit limited movement of the engaging member relative thereto, said means including a spring adapted to 65 resist the load on said engaging member re-

sulting from the friction between the surfaces of the polishing member and the work, means for supplying lubricant to one of said surfaces, and means for controlling the supply of lubricant adapted to be actuated by 70 movement of the engaging member relative to the moving member.

10. In apparatus for supplying lubricant to a polishing machine having cooperating work holding and polishing members and 75 means for causing relative motion between said members for producing relative movement between the coating surfaces of the polishing member and the work, a lubricant supply means having an outlet arranged 80 to discharge lubricant on to one of said surfaces, a normally closed valve controlling said outlet, and automatic means operated by variation of the friction between 85 said surfaces to open said valve when said friction reaches a predetermined value.

11. In apparatus for supplying lubricant and abrasive to a polishing machine having a plurality of work holders and corresponding polishing members, each work holder 90 and corresponding polishing member being adapted to have a relative motion for producing relative movement between the coating surfaces of the polishing member and the work, a circulating system comprising 95 a pipe provided with a plurality of outlets arranged to supply lubricant and abrasive to said coating surfaces, and means for maintaining a constant circulation of lubricant and abrasive in said system, independent 100 of the flow through said outlets, at a velocity sufficient to prevent deposition of the abrasive.

12. In apparatus for supplying lubricant and abrasive to a polishing machine having 10 a plurality of work holders and corresponding polishing members, each work holder and corresponding polishing member being adapted to have a relative motion for producing relative movement between the coating surfaces of the polishing member and the work, a circulating system comprising 11 a pipe extending adjacent to said work holders and polishing members and provided with a plurality of outlets arranged to 11 supply lubricant and abrasive to their coating surfaces, means for maintaining a constant circulation of lubricant and abrasive in said system at a velocity sufficient to prevent deposition of the abrasive, a valve 12 for controlling each of said outlets, and means for intermittently opening said valves.

13. In apparatus for supplying lubricant to a polishing machine having cooperating 12 work holding and polishing members and means for causing relative motion between said members for producing relative movement between the coating surfaces of the polishing member and the work, a lu- 13

bricant supply means having an outlet arranged to discharge lubricant onto one of said surfaces, a valve controlling said outlet, automatic means operated by variation of the friction between said surfaces to open

5 the friction between said surfaces to open said valve when said friction reaches a predetermined value, means for closing said valve, and means adjustable for varying the amount of lubricant discharged upon each

10 opening of the valve.

14. In apparatus for supplying lubricant to a polishing machine having cooperating work holding and polishing members and means for causing relative motion between

15 said members for producing relative movement between the coacting surfaces of the polishing member and the work, a lubricant supply means having an outlet arranged to discharge lubricant on to one of said surfaces, a valve controlling said outlet, automatic means operated by variation of the friction between said surfaces to open said

20 valve when said friction reaches a predetermined value, and means adjustable for varying the time during which the valve remains open.

15. In apparatus for supplying lubricant to a polishing machine having cooperating work holding and polishing members and

30 means for causing relative motion between said members for producing relative movement between the coacting surfaces of the polishing member and the work, a lubricant supply means having an outlet arranged to discharge lubricant on to one of said surfaces, automatic means operated by variation of the friction between said surfaces for controlling the supply of lubricant, and means adjustable for varying the rate of

35 flow of lubricant through said outlet.

16. In apparatus for supplying lubricant to a polishing machine having cooperating work holding and polishing members, and means for causing relative motion between

40 said members for producing relative movement between the coacting surfaces of the polishing member and the work, the combination of means controlled by variation of the friction between the surface of the

45 polishing member and the work to supply lubricant to one of said surfaces when said friction reaches a predetermined value, and means adjustable for varying said predetermined value.

50 17. In apparatus for supplying lubricant to a polishing machine having cooperating work holding and polishing members and means for causing relative motion between said members for producing relative move-

55 ment between the coacting surfaces of the polishing member and the work, the combination of means for supplying lubricant to one of said surfaces, and means operated by variation of the friction between said sur-

60 faces for controlling the supply of lubricant,

said last mentioned means being arranged to cause lubricant to be supplied to such surface at the time when and place where it is exposed by the relative motion between the members.

18. In apparatus for supplying lubricant to a polishing machine having cooperating work holding and polishing members and means for causing relative motion between

70 said members for producing relative movement between the coacting surfaces of the polishing member and the work, the combination of lubricant supply means having an outlet for discharging lubricant on to one

75 of said surfaces, a controlling valve for said outlet, means for applying constant yielding pressure tending to move said valve in one direction, means for opposing to said constant yielding pressure pneumatic pressure

80 tending to move said valve in the opposite direction, and means operated by variation of the friction between said surfaces for varying said pneumatic pressure and thereby actuating said valve.

19. In apparatus for supplying lubricant to a polishing machine having cooperating work holding and polishing members and means for causing relative motion between

85 said members for producing relative movement between the coacting surfaces of the polishing member and the work, the combination of lubricant supply means having an outlet for discharging lubricant on to one

90 of said surfaces, a controlling valve for said outlet, means for exerting constant yielding pressure on said valve in the direction to cause it to open, pneumatically operated

95 means for keeping said valve normally closed and means for supplying pneumatic pressure thereto, means providing a nor-

100 mally closed vent, and controlling means operated by variation of the friction between said surfaces to open said vent to relieve said pneumatic pressure and permit said valve to open when the friction between

105 said surfaces reaches a predetermined value.

20. In apparatus for supplying lubricant to a polishing machine having cooperating work holding and polishing members and means for causing relative motion between

110 said members for producing relative movement between the coacting surfaces of the polishing member and the work, the combination of lubricant supply means having an outlet for discharging lubricant on to

115 one of said surfaces, a controlling valve for said outlet, means for exerting constant yielding pressure on said valve in the direction to cause it to open, pneumatically operated means for keeping said valve normally closed and means for supplying pneumatic pressure thereto, means providing a nor-

120 mally closed vent, and controlling means operated by variation of the friction be-

125 tween said surfaces to open said vent to re-

130

lieve said pneumatic pressure and permit said valve to open when the friction between said surfaces reaches a predetermined value, and an adjustable throttle controlling the pneumatic pressure supply and operative to vary the period of operation of said valve by varying the rate at which, after the pneumatic pressure in the valve closing means has been relieved by the opening of the vent, such pressure is restored.

21. In apparatus for supplying lubricant to a polishing machine having cooperating work holding and polishing members, and means for causing relative motion between said members for producing relative movement between the contacting surfaces of the polishing member and the work, the combination of a yieldable element in the means for causing such relative motion adapted to yield under a predetermined force, means for supplying lubricant to one of said surfaces, and means for controlling the supply of lubricant actuated by the yielding of said yieldable element.

22. In apparatus for supplying lubricant to a polishing machine having cooperating work holding and polishing members, and means for causing relative motion between

said members for producing relative movement between the contacting surfaces of the polishing member and the work, the combination of a yieldable element in the means for causing such relative motion adapted to yield under a predetermined force, means for adjusting said yieldable element so as to vary the predetermined force under which it is adapted to yield, means for supplying lubricant to one of said surfaces, and means for controlling the supply of lubricant actuated by the yielding of said yieldable element.

23. In a polishing machine having cooperating work holding and polishing members and means for causing relative motion between said members for producing relative movement between the contacting surfaces of the polishing member and the work, means for maintaining friction between the surfaces of the work and the polishing member approximately constant comprising the combination of means for varying the friction between said surfaces, and means operated by variation of the friction between said surfaces for controlling the operation of said friction varying means.

WILLIAM TAYLOR.
